SOUND RECORDING AND REPRODUCING APPARATUS

Paul Stead Gay, Charlotte, Mich., assignor to The Wilcox-Gay Corporation, Charlotte, Mich., a corporation of Michigan

Application February 26, 1940, Serial No. 320,823

11 Claims. (Cl. 274—13)

This invention relates to recording mechanisms and more particularly to a phonograph recording mechanism of simplified and novel design particularly adapted for use by non-technical unskilled users.

In the field of sound recording, over a period of years, many producers have built equipment primarily to fill the needs of users concerned with commercial recording. These devices were designed without particular regard for either cost of manufacture, simplicity of operation or mass production requirements, since the field of possible sale was considered limited in number. The purchasers were in the usual case technicians fully capable of operating and maintaining complicated apparatus, and the initial cost of the equipment was not of prime importance due to the nature of their utilization.

For the purpose of developing what seemed to be a much greater field for sound recording, namely, the use of sound recording in the majority of homes for such purposes as the copying of radio programs, the recording and keeping of mementos, personal or business correspondence, musical education and similar elements incident to everyday life, I sought to develop an equipment that would produce sound records of equal or superior quality to those made by the equipment heretofore on the market but that could be made easily in mass production at a low cost and would in a major way be self-adjusting and would be simple for the layman to operate.

The inventions thus developed and herein described fall into two groups; first, those having to do with the securing of high quality recordings with equipment capable of producing these results yet less expensive to manufacture than existing equipment because of better fundamental design, and in the second group, inventions having to do with the simplifying of the equipment so that non-technical people can operate it without difficulty.

Each of these two major developments and requirements are however closely interrelated since many of the elements for producing improved results at greatly reduced cost also include simplifying elements which facilitate non-technical unskilled operation.

The primary object of the present invention therefore is the provision in sound recording apparatus of means for producing high quality recordings with simplified inexpensive equipment, and, concomitantly, the arrangement of the sound recording equipment to facilitate use thereof by the unskilled amateur consumer.

In the average recording instrument of the prior art, the various mechanisms thereof have been separately built into and mounted on the instrument. After the mounting and assembling phase of the work was completed, a great deal of alignment and general adjustment was required in order that the instrument might be made to function as an integral unit.

One of the objects of the present invention is to so arrange the various portions of the recording mechanisms that they may be associated as a complete unit without the necessity for complicated alignments and adjustments. This is accomplished not merely by the mounting of all of the mechanisms on a single base plate which may thereafter be inserted in a proper enclosure, but is likewise accomplished by the arrangement of the various parts of the instrument, each of which is so constructed as to readily cooperate with each of the other parts without any necessity for undue adjustment.

It may be noted in passing that while the emphasis of the present invention is on recording mechanisms and while the recording mechanism is described as an integral unit, the pick-up of a phonograph sound producing instrument may be also integrally mounted in unitary association with the recording mechanisms to be selectively placed in contact with a recording disk on the turn-table for reproducing sound.

By this means, every piece of mechanism which has any mechanical movement whatever (even though said movement is electrically induced) may be readily associated in a single unit with every other such piece of mechanism and every member is so arranged that it may be self-adjusting with respect to the other members of the unit without the necessity for alignments of various types.

An object of this invention therefore is the arrangement of the various mechanical portions of a recording instrument in a single unitary assembly which need not require alignment or adjustment.

Another object is to unite in a single unit assembly all the mechanical components for recording and transcription so that they inherently meet adjustment procedures and so that the whole becomes a unit which can be placed in any equipment while nevertheless retaining all of its adjustment characteristics and all of the elements of operation.

A valuable result of this interrelationship and self-adjustment is that the equipment may thus be designed to meet standard mass production

procedures, resulting in economy and speed of manufacture. While the resultant simplification in equipment, as well as in adjustment, alignment and operation, brings the recording apparatus into the realm of immediate use by the unskilled operator by reason of both its economy and simplicity.

In the present instrument in order that it may be used conveniently by inexperienced non-technical consumers in their homes it has been necessary that any avoidable elements which might in any way interfere with or make more difficult the recording process should be avoided.

One important disturbing element where electric motors are used in order to drive the turn-table and other mechanism of the recording instrument is the vibration inherent in the operation of the motor. Thus, for instance, where an induction motor is used, the forces applied thereto during a single revolution vary in accordance with the momentary position of the energized components of the armature with relation to the field poles, there being then an alternate increase and decrease of rotational force.

If the vibration induced by this momentary and continually recurrent change in the speed of rotation were reflected in the operation of the turn-table, then this may cause a change in the recorded frequency which manifestation is commonly known as "wows."

Heretofore, any attempt to overcome this cyclical variation in the power pulse has depended upon a heavy rotating mass, that is, the turn-table, in effect, was made a heavy fly-wheel so that its inertia might overcome the cyclical variations in the power transmitted by the motor. Such expedients rendered the entire unit extremely heavy and expensive and more difficult in manufacture and operation.

In the present invention it has been found that a constant cyclical effective speed of rotation of the motor with respect to the turn-table may be obtained by suitable flexible mountings which are so arranged as to absorb any small cyclical speed variations or eccentricities.

An important object of this invention, therefore, is to so arrange the electric motor and the mounting thereof with respect to the recording unit that although it is an integral part of the unit, the said unit may be insulated from the vibrations induced thereby. This is preferably accomplished in the present invention by a resilient mounting of the motor and by a frictional speed reduction arrangement, the principal reliance being, however, placed on the resilient mounting and the resilient connection between the motor and the turn-table, through a rubber rimmed idler.

Heretofore also in recording units of various kinds, various complicated expedients and difficult adjustments were necessary to operate the cutting arm, such difficulties being present not only in the means of actuating the arm itself in relation to the turn-table, but also in the means whereby the arm might be connected and disconnected from operation. Various complicated gears, cams, and interrelated and inter-engaging clutches have heretofore been necessary to operate the cutting arm, that is, to produce the lateral feed thereof with respect to the turn-table. And additional clutches and interengaging mechanisms which required separate operation were also necessary in order to engage or disengage the cutting arm from the influence of its lateral feed.

Still another important object of this present invention, therefore, is to so arrange the cutting arm of the recording equipment that the mere position thereof determines its engagement with a lateral feed and so that no other mechanical equipment is necessary to orient the lateral feed with the rotative movement. This may be accomplished in several ways, a preferred method being the driving of a helix from the main shaft of the turn-table or from any other suitable source and the engagement of an extension of the pivoted base of the cutting arm with the helix, the position of the cutting arm (raised or lowered) being the sole determinant of the engagement of its extension with the helix.

This object and the means of effecting it further emphasize the principal object of the present invention which is the integrating of the entire assembly into a single unit. And it should be noted that the purpose is not merely mounting all the members on a single plate but actually so associating the various operating members that the operation and function of each is directly related to and dependent upon the operation and function of all of the others.

In prior recorder designs, emphasis was placed on the utilization, in the first instance of a record disc having an absolutely true surface. Since absolute trueness is, for practical purposes, an impossibility due either to wobble of the turn-table itself or to irregularities in record surface, it is therefore necessary to create a design which will cut a satisfactory even groove into the surface of the record which moves it up and down.

Another object of the present invention is to so arrange the cutting head suspension in the cutting arm and the cutting stylus carried thereby that changes in record height, irregularities in record material or manifestations ordinarily described by table wobble, do not effect the smoothness or depth of the groove being cut, the while, by the cutting stylus, and hence because of this arrangement the table velocity remains unchanged.

Other objects of the present invention include the provision of simplified indication of recording level volume, novel means for collecting and removing shavings and a novel arrangement of the play-back arm.

Still other objects and uses of the present invention will in part be apparent and in part pointed out in the following description and drawings in which:

Figure 1 is a view in perspective of the recording unit assembly with the turn table removed.

Figure 2 is a cross-sectional view taken on line 2-2 of Figure 4 looking in the direction of the arrows and showing the cutting arm of the recording unit of Figure 1 in lowered position so that the stylus engages the disk upon which a record is to be made.

Figure 3 is a view in perspective of the stylus. Figure 3a is a cross-sectional view on line 3a-3a of Figure 3.

Figure 3b is a cross-sectional view on line 3b-3b of Figure 3.

Figure 3c is another perspective view from the opposite side of Figure 3.

Figure 4 is an elevation partly in cross-section taken on line 4-4 of Figure 1 showing the turn-table in place upon its post and the cutting arm and stylus thereof in engagement with the disk upon the turn-table.

Figure 5 is a top plan view partly broken away

of the recording assembly of Figures 1 and 4 taken on line 5—5 of Figure 4.

Figure 6 is a cross-sectional view on line 6—6 of Figure 5.

Figure 7 is a cross-sectional view on line 7—7 of Figure 4.

Figure 8 is a partly schematic top view of the cutting arm in place upon a rotating record disc showing the shaving collector in use.

Figure 9 is a partial cross-section of the play-back arm taken on line 9—9 of Figure 1.

Figure 10 is a cross-sectional view partly in elevation taken along line 10—10 of Figure 9, looking in the direction of the arrows.

Figure 11 is a diagrammatic illustration of cutting head behavior at three possible phases of operation.

Figure 12 is a graph of the action of the cutting head suspension at three possible phases.

Figure 13 is a graph of the effect of various forces on the depth of the groove produced by the cutting stylus.

Referring now to Figure 1, there is here shown in perspective the base plate 10 of the recording assembly having the form which it takes when mounted in the top or other portion of a cabinet or other unit. The base plate 10 carries secured thereto by screws 11 or any other suitable means a mounting plate 12 which registers with any necessary or suitable orifices in the base plate 10 which it however covers. The mounting plate 12 carries on its upper surface the various driving mechanisms hereinafter described, but it should be noted that a turn-table hereinafter described mounted on the turn-table post 13 covers mounting plate 12 entirely and thus conceals the various mechanisms protruding above the top thereof.

The drive mechanism for the lateral feed of the cutting arm comprising the arm and helix beneath the base plate 10 and hereinafter described obviously is not visible when the base plate 10 is mounted in the top of its cabinet.

In the following explanation, reference particularly to Figures 2, 4 and 5 as well as Figure 1 will serve to further illustrate each of the parts herein mentioned.

The drive motor 14 of the recording unit (seen particularly in Figures 2 and 4) is resiliently mounted on the mounting plate 12 on latex rubber gromets 15, 15 (see also Figures 2, 4, and 5). By this means the motor 14 is completely dissociated from the remainder of the mechanism since the only connection of the motor therewith is through the mounting 15. The shaft 16 of the motor projects through an opening in the mounting plate 12, the opening being of sufficient width that no contact is made by the shaft with the mounting plate 12. (See Figures 1 and 5.)

The shaft 16 carries an arbor 17 (Figures 1, 2 and 5) which is of the exact diameter so that when engaged with the rubber rim 18 of the idler 19 which in turn engages the inner surface of the flange 20 (see Figure 4) of the turn-table 21, will produce a predetermined reduction of speed resulting in a rotation of the turn table 21 at a predetermined speed.

Thus, in addition to the resilient mounting of the motor which disassociates the motor from the mechanism, the connection from the motor to the turn table is not a direct rigid mechanical connection but is a frictional and resilient connection by reason of the interposition of the

rubber tired idler 19 between the driving arbor 17 and the turn-table.

As seen particularly in Figures 1, 5 and 6, the idler 19 is not mounted directly on the mounting plate 12, thus further tending to dissociate any vibrations which may be induced even in the mounting plate by the motor from the main drive of the turn-table itself.

The idler 19 is mounted on the sliding arm 22 which is retained in its association with the mounting plate 12 by means of the screw 23 passing through mounting plate 12 and through an enlarged perforation 24 in the arm 22. A washer 25 is placed over the screw 23 and is so arranged that it will at all times cover the large perforation 24 and lock nuts 26 are applied to the end of the screw.

The lock nuts comprise preferably two nuts which may be tightened against each other in such a manner that the washer 25 is not pressed tightly against the arm 22 so that the arm may slide upon the mounting plate 12 and is limited only by the abutment of the periphery of the perforation 24 against the screw 23. This gives the arm a predetermined amount of play with relation to the mounting plate 12 and correspondingly gives the idler 19 supported thereby a degree of play with respect to the arbor 17 of the drive shaft 16.

A lug 27 struck up from the mounting plate 12 registers with a slot 28 of the sliding arm in order to guide its movement so that the movement thereof will be in such direction as to cause the idler 19 to be in contact with the arbor 17 under virtually all conditions.

Spring 29 captured at 30 in the mounting plate and guided by the lug 31 struck up from the mounting plate engages a lug 32 of the sliding arm in order to tend to drive the idler away from the arbor, exerting just sufficient force for this purpose. The turn-table 21 preferably is of such diameter that when mounted upon the turn-table post 13, the inner surface of the flange 20 thereof will press the idler 19 against the arbor 17 so that motive power may be transmitted to the turn table from the arbor 17 by frictional engagement thereof with idler 19 and by frictional engagement of the rubber rim 18 of idler 19 with the inner surface of the flange 20 of the turn-table 21.

The turn-table 21 may be weighted by means of a flat plate which is welded on top of a conventional phonograph turn-table.

The radius therefore of the turn-table should be such as to force the idler 19 against the arbor 17. Should the radius be slightly smaller, then the position of the idler 19 with respect to the arbor 17 is self-adjusting. That is, instead of the idler being forced directly against the arbor 17, it will by reason of the fact that the perforation 24 is much larger than the screw 23, be caused to come in contact with the arbor 17 not at the point towards which the idler has been forced; but the position of the pivot 33 of the idler 19 with respect to the arbor 17 will have been moved arcuately several degrees away from that which it would have assumed at the first position of contact above-mentioned. Thus in Figure 5 the position of the perforation 24 of the arm 22 with respect to the screw 23 is shown as a position wherein the turn table 21 is of the smallest radius, the pivot 33 having been moved several degrees clockwise from its original position with respect to the arbor 17.

A turn-table of slightly larger radius will per-

mit the perforation 24 of the sliding arm 22 to assume a position so that the screw 23 will be somewhat centrally located with respect thereto while when the turn table 21 is completely removed, the screw 23 will be in a position along the periphery of the perforation 24 which is approximately 120° removed counterclockwise from the position shown in Figure 5.

Thus it will be seen that with the turn-table 21 mounted in place upon its post 13, operation of the electric motor 14 will result in rotation of its shaft 16, thus resulting in rotation of the arbor 17 carried thereby. The frictional engagement of the arbor 17 against the rubber rim 18 of the idler 19 will result in rotation of the idler and the frictional engagement of the rubber rim 18 with the inner surface of the flange 20 of the turn table 21 will result in corresponding rotation of the turn-table.

The diameters of the arbor, idler and turn-table may be so arranged as to provide for the requisite speed reduction from original motor speed to turn-table speed. There is no possibility of the transmission of motor vibrations or of characteristics resulting from uneven motor operation to the turn table itself since the motor is resiliently mounted with respect to the mounting plate 12 and has only a frictional engagement through a resilient rubber rim 18 with the turn-table.

Examination of the figures will thus show that there is no place where the motor is not resiliently isolated from the turn-table and the rest of the assembly. Such resilient isolation of the motor is of real importance where it is desired to dampen out the power pulse generated where an induction motor is used. During any 360° cycle of rotation of the motor, the energized portions of the armature assume different positions with respect to the field poles thereby causing an alternate increase and decrease of rotational effect.

If the motor were directly connected to the turn table or if it were so arranged in association with the turn table that there were no resilient connection therebetween, a high frequency "wow" would result. The resilient mounting and resilient connections above described result in the motor vibrating back and forth against its resilient mounting in accordance with and in a direction to compensate for the proportional variation in speed and thereby irons out this variation.

This solution presents what is believed to be a completely novel application of D'Alembert's principle of dynamics that a moving mass exerts inertia reaction forces proportional to the inertia of the mass and its acceleration. Heretofore it has always been thought necessary to mount the motor solidly and immovably so that the mass thereof may have sufficient purchase to transmit a driving force through the shaft. In the present invention the important element is that the field poles, or in other words, the mass of the motor itself, is resiliently mounted, the armature and shaft of the motor being connected and mounted in the ordinary way between the poles. Any sudden increase in the power, that is, any power pulse, impinged upon the rotating shaft will result in a counteracting reaction in accordance with D'Alembert's principle. This counteraction is not caused to take place against a solid immovable mass but, by reason of the resilient mounting of the main mass of the motor, the inertia reaction results in a definite movement of

the mass of the motor of sufficient moment to counteract the power pulse, thus dampening out the power pulse and resulting in a net rotation of the shaft with respect to the turn-table which is not increased by the power pulse.

This resilient mounting of the motor and isolation thereof from the recording equipment, that is from the equipment which is actually to make the record, is a distinct improvement which has been found to be of real value in actual commercial operation. It is important, however, that while isolation of the power pulse be effected and while all sources of vibration or all sources which may result in the creation of disturbing noises in a recording, be obviated, the various portions of the apparatus be integrated in their operation so that they are mutually interdependent and constitute together a single complete unit.

In the present device, the compressing of the tire 18 on the idler 19 does not at any time substantially change the speed ratio between the pulley 17 of the motor and the flange 21 of the turn table, since irrespective of the extent to which the tire 18 may be compressed, the linear speed of the tire 18 induced by its contact with the pulley 17 of the motor is translated by its contact with the flange 21 into a linear speed for the flange 21 of the turn-table which is always substantially equal to the linear speed of the pulley 17. Where this condition is not fulfilled, vibration causing a change in compression of resilient members will produce "wows."

The resilient mounting of the motor and the isolation thereof from the recording equipment, that is from equipment which is to make a record of sound and the consequent mechanical filtering of torque pulsations and similar vibrations is believed to be novel.

Screw 210 may be so arranged in the journal of post 13 that it may be rotated inwardly to engage the annular groove 211 thereof (Figure 2) to prevent the post or spindle 13 from falling out during shipment. The screw may be rotated out of engagement with groove 211 after shipment; or the groove may be sufficiently wide so that the screw does not bear against any portion of spindle 13 when the mechanism is arranged in upright position.

An important element of the present assembly is the integration of the cutting arm and the lateral feed mechanism thereof with the remainder of the assembly and a most important element to be observed is that the lateral feed of the cutting arm is directly related to the position of the cutting arm, that is, a mere change in position of the cutting arm will result in connecting the arm to the lateral feed or disconnecting the arm therefrom.

Another important element to be noted in the operation and construction of the cutting arm is that the cutting arm is not driven directly from the motor in any way whatever so that the motor is completely isolated therefrom but the drive of the cutting arm is from the turn-table mounting post thus introducing further elements of isolation between the cutting arm itself and the motor which forms the ultimate source of power therefor.

Likewise, the arrangement of the cutting head in the cutting arm is such that further and complete isolation of the cutting stylus from the motor is insured while nevertheless the cutting arm is ultimately driven by the power of the motor.

The cutting arm 34 (Figures 1, 2, 4 and 5) is pivotally mounted by means of the pins or screws 35 on the platform 36. The cutting arm 34 may

rotate about the pins 35 with respect to the platform 36 in a vertical plane only so as to assume for instance the position shown in Figures 2, 4, and 5, but any rotation of the cutting arm 34 in a horizontal plane will result in rotation of the platform 36 and likewise any rotation of the platform 36 horizontally will result in rotation of the cutting arm.

The platform 36 is keyed to and mounted upon shaft 37 in such a manner that shaft 37 and platform 36 must necessarily rotate together. Shaft 37 is rotatably carried in the journal 38 which is mounted upon the base plate 10, the shaft 37 extending beneath base plate 10 and carrying at the bottom end thereof and keyed thereto so as to rotate therewith the lateral feed arm 39. The shaft 37 may also slide vertically in the journal 38.

A compression spring 40 is mounted between the lateral feed arm 39 which constitutes virtually a right angle extension of the shaft 37 and the bottom of the base plate 10, thus exerting a downward force upon the shaft 37.

Raising the shaft 37 will therefore result in a raising of the lateral feed arm 39 and lowering of the shaft 37 will result in a corresponding lowering of the lateral feed arm 39.

The means for raising and lowering the shaft 37 in order to cause a raising and lowering of the lateral feed arm 39 is a direct function of the position of the cutting arm 34, that is, when the cutting arm 34 is in the position shown in Figure 1, the lateral feed arm 39 is raised and when it is in the position shown by the solid line of Figure 2 the lateral feed arm is lowered.

This raising and lowering of the shaft is accomplished by the pivoted mounting in a vertical plane of the cutting arm 34 on the pins 35 and by the pivoting links or lift levers 41, the said links being rotatably connected at 42 to the cutting arm and rotatably mounted in the notches 43, 43 of the platform 44.

The platform 44 is carried by the journal 38 and is fixedly arranged with reference to its height above the base plate 10 and does not rise or fall with the shaft 37. It is held in fixed vertical position by means of the engagement of an inner annular portion thereof in the annular groove 45 of the journal 38 so that while it may rotate with respect to the journal and not impede the horizontal rotation of the platform 36, and its associated shaft 37 it may not change its vertical relation with respect to the base plate 10.

For purposes of the following description, the pin mounting 35 of the cutting arm and the notch mounting 43 of the link 41 may be regarded as the end pins of a toggle mechanism, while the rotatable mounting 42 of the link 41 in the cutting arm 34 may be regarded as the knee pin of the toggle mechanism; that is, the toggle may then consist of an imaginary link 35-42 and link 41 rotating about the knee or knuckle 42. When the elements are in the position shown in Figure 1, then imaginary link 35-42 is not in alignment with link 41 but extends counterclockwise thereof.

When the cutting arm is lowered, then by reason of the rotation of the cutting arm 34 about the pin 35 and the consequent movement of the rotatable pivot 42 of the link also in a clockwise direction, the first tendency is to bring the imaginary link 35-42 into alignment with the link 41. In other words, the movement of the pin 35 with respect to the knee pin 42 is counterclockwise. The initial movement necessary to bring the pivot mounting 35-42 into alignment first results in a slight raising of the shaft 37 against the force of

the compression spring 40. Then as pin 35 in its counterclockwise movement with respect to pin 42 passes out of alignment therewith, the tendency of the compression spring 40 acting on shaft 37 which in effect therefore acts on pin 35 is to bring the end pins 35 and 42 of the imaginary toggle mechanism close together and to force the pin 42 out thus resulting in the tendency of the compression spring 40 acting on shaft 37 to draw the cutting arm into downward position and to lock the cutting arm into downward position.

By this relative arrangement of the rotatable mounting 42 of the link 41 with respect to the rotatable mounting 35 of the cutting arm 34 and by the production of the toggle effect above described, the compression spring 40 operates to engage the cutting arm in raised position when that is desired so that the cutting arm will not fall accidentally and thus injure the stylus or destroy a record underneath and likewise to engage the cutting arm in lowered position and hold it in lowered position by the spring action of spring 40.

There is, in other words, the true snap action of a toggle wherein the same force may be utilized to drive the end pins of the toggle together, no matter which side of the aligned position one toggle extends with respect to the other. There is then what may be less technically called locking action owing to the operation of spring 40 which locks the cutting arm in raised vertical position against any possibility of accidentally falling and likewise locks the cutting arm in lowered position. Both means depend on the operation of spring 40 which is so arranged that manual engagement of the end of the cutting arm by the clasping of the finger buttons 46 (Figure 1) will be sufficient to overcome the action of spring 40.

The toggle action herein described and the action of imaginary link 35-42 in connection with the link 41 and the action of both about the pin 42 is clearly shown in the solid and dotted lines of Figures 2.

It will be noted, however, that when the cutting arm 34 is in a raised position, the tendency of the spring 40 to pull it down is counteracted by the fact that the tops of the links 41 press against the bottom edges of the flanges 47 of the platform 36 and that the spring is thus prevented from pulling the platform down; and when the cutting arm 34 is lowered, then the only element which prevents the pulling of the platform down is the pressure of the cutting arm 34 against the adjustment screw 48 on the platform. (See Figures 1 and 2.)

This adjustment screw may be so arranged as to insure that the cutting arm is at the proper position in the cutting head to function correctly and to further insure that the lateral feed arm is properly engaged with its drive mechanism.

The cutter arm lift lever therefore is so arranged as to go past dead center position, locking the arm in raised position against any possibility of falling.

The cutter arm lift lever 41 also provides a thrust along the length of the arm which acts to take up slack and whatever lost motion exists.

Spring 46 is provided to assure complete downward travel of the pivot post shaft when the cutter arm is lowered. This spring is necessary since the cutting arm itself may not be of sufficient mass to secure the locking previously described in the

raised position or the proper pressure in the lowered position.

The height adjusting screw 48 is provided for positioning the cutter arm vertically and obtaining the proper height of the knife edge pivots, hereinafter described, relative to the record surface. Locking nut 48a provides for permanence of the selected adjustment.

When the cutter arm is lowered so that it is pressed upon the height adjustment screw 48, the cutting head is practically in its normal operating position and equilibrium of cutting conditions is obtained automatically if the record surface is rotating or when the record starts rotating.

The height adjusting screw 48 controls what could be called normal conditions. The adjustment of this screw is necessary to strike an intermediate position so that the cutting angle may change above and below the normal value and the spring action still compensate for the changes that would otherwise occur in groove depth.

The drive mechanism of the lateral feed arm operates from and is a direct function of the rotation of the turn-table. The operating mechanism comprises a rotating helix, spiral or screw 49 (Figures 1, 4 and 5) which is operated by the worm and spiral gear arrangement 50-51 shown in Figure 2, the spiral 50 being an extension of the turn-table mounting post 13. Rotation of the turn-table resulting in rotation of the spiral 49 results in rotation of the gear 51 which results in rotation of the helix or helical screw 49 to which it is attached.

The lateral feed arm 39 keyed to the shaft 37 carries at the opposite end thereof a pawl 52 which registers with the threads of the helical screw 49. As will be noted from Figure 2, when the cutting arm is lowered, it, in the manner hereinbefore described, causes the lateral feed arm 39 to be depressed. This depressing of the lateral feed arm 39 causes the pawl 52 to engage the threads of the helical screw 49. And in the manner hereinbefore described, raising of the cutting arm 34 causes a corresponding rise of the shaft 37 and a corresponding rise of the lateral feed arm 39, thus disengaging the pawl 52 from the threads of the helical screw 49 in the manner shown by the dotted lines of Figure 2.

To make assembly rapid and obviate the necessity for holding to close tolerances in the machining of the assembly, the lateral feed arm does not itself directly carry the pawl which engages the helical screw but a resilient means is provided between the arm and the pawl. The provision of such resilient means results in the effect that any deviation from trueness in the lateral feed will not cause an uneven power demand from the motor resulting in "wows."

Cantilever spring 53 is attached by means of rivets 54, 54 to the lateral feed arm 39. The free end of the lateral feed arm 39 as seen particularly in Figure 2 carries adjustment screw 55 which may be raised or lowered to adjust the pressure of the cantilever spring 53 after the assembly is completed, a lock nut 56 making the adjustment a permanent one.

The pawl need not be a separate piece of material, but for purposes of economy as well as ease and simplicity of manufacture, the pawl 52 may merely be a lug or flange struck up out of the material of the cantilever spring thus integrating the pawl with the remainder of the lateral feed arm.

It will thus be seen that rotation of the turn-table mounting post 13 which results in rotation

of the helical screw 49 will also result in a lateral feed of the cutting arm 34. That is, as the helical screw rotates in the manner hereinbefore described, the pawl 52 will be carried progressively and steadily inward upon the threads of the helical screw 49 toward the turn-table mounting post 13 resulting in the lateral movement of the cutting arm 34 from the periphery of the recording disc toward the center thereof.

It has been usual in the design of recording instruments to use sectors, gears, heart-shaped cams and other similar elements to provide the lateral motion for the cutting arm.

Not only are these means expensive, but they are involved and mechanically complicated, requiring intricate and extremely exact adjustment. The pawl of the present device contacts the lateral feed or helical screw 49 in such a manner that when positioned in the center of the helical screw, then the feed arm is at right angles to the axis of the said helical screw. This minimizes variations in groove spacing.

This same driving principle may be utilized where the follower or feed arm and the cutter arm are at an angle with respect to each other upon their common shaft. Likewise, the same principles may be utilized to maintain substantially uniform groove spacing.

This results in a movement of the cutting head which follows a cosine law, resulting in the grooves being further apart in the center of the record than they are at either the outside of the record or the inside of the record. However, the extent to which they are nearest or furthest apart depends upon the cosine of the angle of the lateral feed arm to an imaginary perpendicular erected on the lateral feed worm or helical screw at the point of contact, this angle being small for all values by reason of the length of the lateral feed arm and the distance of the shaft 37 from the helical screw 49 and being zero when the arm is in the center of the worm at an angle of 90° thereto; the variation is small and the economy and mechanical perfection and simplicity of the device more than compensate for the slight difference in the spacing apart of the grooves of the record.

A stop 48a is provided for the lateral feed arm to prevent the carrying of the cutting stylus too close to the center of the recording disc.

The worm driving the feed screw is integral with the turntable shaft; the feed screw by reason of the fact that it is driven from the shaft of the turn-table is thus resiliently isolated from the driving motor in the same way that the turn-table itself is resiliently isolated, that is, the power transmission path from the motor to the feed screw includes the rubber tire 18.

The worm and pinion driving the feed screw are totally enclosed. The benefit is one of keeping foreign material of any sort, for instance shavings or dust, completely clear of the gear teeth.

This type of construction permits practically permanent lubrication because the enclosure may be literally filled with lubricants.

The worm provides lifting action to the lubricants while gravity is opposed and a circulation of lubricant results.

The screw 55 and locking nut 56 are provided to properly adjust spring member 53 minimizing the necessity for accuracy which would otherwise be required in the remainder of the assembly and to promote an optimum spring pressure.

The follower arm knife edge and the compliant or resilient member are preferably a one piece stamping.

Vertical compliance is provided between the follower arm and its knife edge which (a) minimizes the accuracy required in vertical alignment; (b) provides a certain amount of mechanical filtering to minimize transmission of vibration between feed screw and follower arm; and also takes care of whatever eccentricity may exist in the feed screw regarding vertical adjustments; (c) will act as a clutch in case the follower arm reaches the limit of its allowable travel and brings up against the stop 49a; in which case the knife edge will ride up the side of the thread of screw 49 and fall back into the groove.

The cutting head 60 (see Figures 1 and 2) is resiliently mounted in the cutting arm 34. The cutting head comprises a member 61 which is responsive to amplified voltage impulses transmitted thereto by the wire 62, the said member carrying a stylus 63 to which are transmitted vibrations corresponding to the impulses received by the microphone.

The cutting head 60 carries a plate 64 riveted to the back end thereof, the said plate 64 having a knife edge which abuts against the angle 65 of the member 66. The plate 64 also carries a perforated extension 67 which may be engaged by the tension spring 68. The member 66 is riveted to the flat plate 68a which is extended to the flat plate 68 which in turn is secured by the screws 70 to the cutting arm 34. The mounting plate 68 carries at the rear end thereof the U-shaped channel 71 in which the screw 72 is mounted. The screw is arranged so that it may rotate with respect to the flanges of the U-shaped member 71 without moving longitudinally with respect thereto. The head of the screw 72 projects through a perforation in the top of the cutting arm so that it may be accessible for the adjustment purposes hereinafter noted.

The cutting head is maintained in resilient suspension by engagement of the spring 68 with the perforated projection thereof 67 and by engagement of the opposite end of the spring 73 with the threads 72. The end of the spring 73 comprises a small perforated plate through the perforation of which the screw 72 passes, the periphery of the perforation engaging the thread of the screw. Rotation of the screw 72 will cause the end 73 of the spring 68 to rise or fall in accordance with the direction of rotation of the screw and thus adjust the suspension of the cutting head 60. The stylus securing screw 14 which is located in the front of the cutting head projects through an oblong opening 75 in the front of the cutting arm, the said oblong opening permitting the raising or lowering of the cutting head either by reason of the change in the suspension or the raising of the stylus in the manner hereinafter noted.

The total possible vertical movement at the cutter head is restricted by the screw 14 in the slot 75 so that the arm can be raised and lowered as a single unit with one hand.

While the raising or the lowering of the end 73 by means of the rotation of the screw 72 adjusts the angle of suspension of the cutting head 60, the spring nevertheless is preferably of sufficient length that the tension of the spring will not vary but rather that the axis of the spring connection changes, that is, the spring pulls in a different direction. In this way, the angle of suspension of the cutting head may be adjusted without changing the degree of resilience of the mounting. It will be noted that should the end 73 of the spring rise, the angle of suspension is

such as to permit the stylus end of the cutting head to ride lower within the cutting arm while should the end 73 be depressed, the stylus end of the cutting head will ride higher.

This knife edge fulcrum 64 provides for a playless bearing for the cutting head and therefore provides for a high degree of lateral stability by virtue of the spread between the contacts.

The spring suspension by means of the spring 68 serves further to maintain a constant power demand from the motor when its tension is correct. The spring in correct adjustment has the net effect of decreasing the total weight of the cutting head and when the head is moved up in the case of a record that wobbles, the amount of spring tension becomes proportionately less.

However, the spring should be and is long enough so that the proportionate amount of variation in tension should be of no consequence. The importance of this will be understood from the following description of the mounting and operation of the stylus end of the cutting head.

Previously in the design of recording equipment, the hope of obtaining freedom from low frequency "wows" lay in the provision of a table with great weight so that the kinetic energy stored in this revolving mass would iron out any change of rotational speed. Unevenness of table velocity is caused by a change in the power demand from the motor; that is, when the power increases, the motor slows down and when it decreases, it speeds up again.

One of the most important reasons for the unevenness in the power demand arises from a wobbling or vertical movement of the recording disk or irregularities in the surface thereof also resulting in vertical movement.

The present invention seeks to solve this problem not by the addition of rotative mass to the turn-table but by proper provision in the cutting head suspension, that is, by the formation of the suspension herein described which results in a practically constant power demand from the motor.

The possible difficulties arising from such vertical movement are, first of all, a variable depth of groove and, secondly, a variable power demand on the motor driving the turn-table.

The first difficulty results in a record which is unsatisfactory in its mechanical nature. The second difficulty results in a recording which was not made at a constant speed. If this record is played back with the constant turn-table speed, the pitch of the sounds recorded will as a result vary. This phenomenon is commonly known as "wows."

The principal work done by the motor driving the turn-table is that of removing the shavings from the record. That is in addition to the relatively constant power demands occasioned by frictional losses inherent in any such assembly.

If for any cause, the size of the shaving is altered, the power drawn on the motor is correspondingly altered.

There are two principal factors affecting depth of cut or size of shaving. The first is the pressure on the stylus and the second, the angle at which the stylus cuts. In my design, variations in these two factors were made to oppose each other so that a substantially uniform shaving resulted, even though the height of the record surface varied.

The change in pressure required was obtained through spring action and the change in cutting angle resulted from the changing height of the

record surface with respect to the point at which the cutter head was pivoted.

As seen in Figures 3, 3a, 3b, and 3c, the cutting face 17 of the stylus is initially ground to a critical angle. That is, when the stylus is inserted in the chuck 18 of the cutting head (see Figure 1) and engaged therein by the screw 14, the flat surface 19 of the stylus determining the position of the stylus in the perforation, the angle of the cutting face 17 is such that with the turn-table continually rotating in a single plane, a groove of optimum depth is cut.

Emphasis should be placed upon the formation of the cutting stylus itself as shown in Figures 3 to 3c as well as in Figure 2 where instead of having the usual large angle between the face of the stylus and the surface of the record, the initial angle is smaller. In this manner, automatic adjustment of the cutting angle in accordance with the momentary height of the turn-table at the point of cutting becomes more readily possible. The cutting angle is such that even though there should be a relatively great amount of vibration in the turn-table, for any reason, resulting in an unusual increase in height at the moment of cutting, there will nevertheless be a sufficient angle to permit cutting.

For purposes of further definition, the cutting angle will be understood to be the angle between the cutting face 17 of the stylus and the surface of the record, measured in the frontal plane. The cutting angle is so arranged that when a small variation in this angle is brought about, by a raising of the stylus owing to a wobble of the turn-table and a consequent moving up of the cutting head, there is a tendency for a less deep groove to be cut and when it goes down, there is a tendency for a deeper groove to be cut.

ANALYSIS OF MECHANICAL BEHAVIOR OF CUTTER HEAD SUSPENSION

I. Static condition

Referring now to the diagrammatic illustration of Figure 11 at the left (at L) is shown the conditions obtaining when a low record surface is encountered. The cutting angle is large. Counter-balancing the effect of this cutting angle is an opposed spring tension which is relatively large. The arrows indicate the magnitude of these forces and their sum is shown as a resultant. The second position (at N) corresponding to a normal surface shows that the cutting angle has been decreased and the axis upon which the spring operates has been changed and the tension of the spring has also been decreased, giving a larger resultant pressure on the stylus which off-sets the effect of the changed cutting angle.

In the present design, the axis of the spring is changing to a predominant degree over the change in tension. Dependence on variation of spring tension may produce unpredictable pressure results, while with a minimum variation in tension, changes in the axis of the spring will produce predictable and regulatable variations in the net effect thereof.

The third position (at H) corresponding to a high record surface shows this same phenomenon carried further. It can be seen that the resultant pressures on the stylus increase as the height of the record surface increases and the cutting angle decreases. It is to be expected, and experience indicates, that the change in cut-

ting depth occasioned by a change in cutting angle will not be a linear function. This means that a complementary non-linear variation in the vertical pressure component derived from the spring tension is desirable.

The diagram of Figure 12 illustrates how this may be accomplished. Pressure on the stylus may be considered essentially equivalent to the torque exerted about the pivot point in the cutter suspension. This torque is a resultant of the weight of the cutter head itself, acting about that point and the spring tension. The spring tension produces torque which is proportional to the product of the tension of the spring itself and the effective length of arm on which it operates. It should also be noted that the effect of change of the axis of the spring itself produces important results in changing the moment about the pivot. Such changes may be utilized to emphasize and equalize the results herein pointed out. There are three positions shown in the diagram.

At point a is illustrated the first point at which we assume the spring is attached to the cutter head assembly. The spring tension is brought about by an extension longitudinal to the line indicated as 1. The effective crank arm is indicated as the perpendicular distance a . Other positions are shown at b and c.

It can be seen that operating at a small angle θ results in changing the effective length of the crank arm at a much greater rate than the extension of the spring as the angle θ tends to increase.

The point at which the other end of the spring is secured is another controlling factor. It can be seen that its positioning with reference to the pivot points and first end of the spring is a factor entering into the control of the effective length of the crank arm. It is apparent that this type of design allows obtaining the exact pressure desired for two positions of the cutter head and a close approach at other points over a wide range.

In other words, if the torque which would be required for each possible positioning of the cutter head is examined, this design permits the obtaining of exactly that pressure at any two selected positions. The curve of torque plotted against vertical positioning of the cutter will thus closely approximate the desired curve by virtue of being the exact value required at two points and of the general form desired at all other points.

Static conditions exist as long as the rate of change of height of the record surface is of low value, since inertia effects depend upon this rate of change. This derivative is dependent not only upon the magnitude of the change but also upon the time within which the change occurs. When this derivative becomes sufficiently large, another factor becomes of importance.

II. The dynamic condition—Stylus pressure due to inertia effect

Whenever the height of the record surface changes, the mass presented by the cutting head is accelerated. The incremental stylus pressure is proportional to the vertical acceleration.

Since this factor is variable in practice, good design requires that the effective mass be kept low, thus keeping the increment low regardless of the percentage variation.

Any conceivable variation in record surface height may be encountered and no design can

completely eliminate inertia effects. The best design then is that of minimizing the magnitude of the effect. The mechanical disposition of the mass necessary in the cutting head is an aid to this end. By locating the pivot point near the center of mass, the moment about the pivot point is minimized.

Since the incremental pressure is a derivative of the vertical displacement with respect to time, the effect on groove depth is in quadrature with the variation in vertical height. This quadrature relationship obviates the possibility of cancelling out its effect by either control over cutting angle or spring tension since they are respectively out-of-phase and in-phase with the record surface height.

In Figure 13 is shown a cycle of variation of record surface height together with the variation in the three effects we have been considering. Curve 2 shows that the effect on groove depth derived from the spring varies in phase with the record surface. (+ in the diagram indicates a greater groove depth; — indicates lesser groove depth.)

Curve 3 indicates the out-of-phase relationship of the cutting angle effect. Curves 2 and 3 may be made to oppose each other as previously described. In case they do not exactly cancel, the resultant sum of these two curves will vary the phase relationship similar to one or the other depending upon which one predominates.

Curve 4 represents the effect due to the acceleration of the mass of the cutting head in the dynamic condition. It can be seen that this wave is shifted 90° one way or the other from any possible combination from curves 2 and 3.

Curve 4 therefore cannot be cancelled, although the cumulative effect may be phase displaced due to its action.

The conclusion to be drawn from the above is that the mass which is accelerated should be kept at a minimum, and its suspension should result in the least possible moment. In the present design, the close positioning of the pivot with respect to the center of mass accomplishes this purpose.

A further design consideration is that involving vertical mechanical resonance occasioned by the mass of the cutting head in conjunction with the spring. Associating any mass with a spring brings about the condition where movement of the mass becomes easiest at some specific frequency. It is desirable in a cutting assembly to be able to follow surface irregularities as rapidly as possible. If the mechanical resonance frequency of the cutting assembly corresponds to a higher rate than the rate at which surface irregularities are encountered, satisfactory cutting may be obtained.

If, however, a surface irregularity exists at a more rapid rate than that corresponding to the resonant frequency of the cutter assembly (the ability of the spring to yield thereto), the stylus will not remain in continuous contact with the record surface.

When irregularities occur at a frequency close to the mechanical resonance of the assembly, the incremental pressures become very much greater in magnitude. Irregularities occurring at a more rapid rate may result in the stylus being lifted completely clear of the record surface momentarily.

"Digging-in" is very apt to occur under such conditions—an action whereby the stylus cuts into the blank very deeply, cuts or tears itself

free of the record surface for a while, and then repeats the cycle.

From the above, it follows that the mechanical resonance frequency of the cutter with its suspension should be made as high as feasible. In addition, in the present design the torque derived from the spring is allowed to actually increase above what other considerations would require to minimize this "digging-in" tendency. The object is to avoid for practical purposes the possibility of a dead center condition beyond which the cutter would tend to bury itself.

The possibility of the occurrence of this phenomenon is of course to a very great extent obviated by making certain that the resonant frequency of the spring is sufficiently high to avoid causing the stylus to clear the surface of the record in the manner above described.

If the lifting action of the spring increases more rapidly than the cutting angle can cause the stylus to bury itself, the cutting arm may be lowered very abruptly to the cutting position and proper cutting equilibrium will automatically establish itself.

In the present assembly, operation by inexperienced users is greatly facilitated by having cutting equilibrium automatically established even though the arm is lowered rather inexpertly.

Summarizing the important features of the above cutter suspension design,

I

(a) Minimizing inertia effects by pivoting the cutter head near its center of mass.

(b) Mounting with knife edges occasions a minimum additional mass and minimum frictional effects.

(c) Horizontal spread between points of contact on knife edges insures continuous axial alignment of the cutting head and high transverse stability.

II

Counteracting changing cutting angles by means of spring action.

This can be done with the spring adding to stylus pressure as well as when the spring subtracts, as is hereinafter described.

III

50. Spring mounting permitting independent design control over

(a) static stylus pressure;

(b) rate of change of stylus pressure with respect to vertical displacement of stylus;

(c) pressure holding knife edges in contact.

IV

A relatively high mechanical resonance frequency of the cutter in its suspension in a vertical plane.

60. As has been pointed out, the present device may be utilized either for cutting records or for playing records which have already been cut. That is, a suitable pick up arm 100 may be provided pivotally mounted at any suitable point on base plate 10 as, for instance, on the post 101 carried by the journal 102 and carrying a needle 103 (Figure 9) for transmitting the vibrations induced by the irregularities of the grooves of an

65. already cut record. In such case, of course, the cutting arm 34, will either be raised not to engage the record at all or rotated to a position where the lateral feed arm is disengaged from and not driven by screw 49. The same turn table may be 70. used for either purpose.

Play-back arm

Some of the features described under the cutter head can be utilized in play-back arms. The problems in play-back are quite similar though not duplicate. In play-back, constant pressure is desired as contrasted with the pressure variation desired in cutting.

A large transverse inertia is desired rather than transverse rigidly with respect to a feed screw (as in the case of the cutting arm). The vertical moment should be held at a minimum as for the cutter. (See Figure 9.)

The play-back cartridge 104 is pivoted by knife edges 105 in an angle bracket 106. This mounting is essentially frictionless for vertical movement of the cartridge 104, while providing for lateral stability and rigidity between the cartridge and the arm. The mass of the arm can be made as large as desired to reduce the frequency of arm resonance, which is that resonance obtained where the mass of the arm works in combination with the compliance of the needle suspension and is ordinarily a low frequency.

A substantial portion of the needle pressure is derived from spring tension of spring 107 attached at one end to the lug 108 of the cartridge and at the opposite end to adjustable bracket 110. Bracket 110 is hingedly mounted at 111 and may be adjusted for correct spring tension by screw 112 which adjustment may be locked in position by lock nut 113. The entire assembly is carried by the plate 114 which is mounted in arm 100 by screws 115. Pivoting the cartridge near its center of mass keeps the vertical moment low; thus minimizing incremental pressures due to inertial effects when variable record surface heights are encountered.

A low vertical movement results in tracking ability (ability to follow a groove of a record and the ability of the needle to stay in the groove) when rapid vertical irregularities are encountered, since the resonant frequency (mechanical) in the vertical plane is raised when the moment is decreased.

The spring applies its force in accordance with the principles described above in relation to the cutting head and in relation to Figure 12. The rotating effort thus applied to the cartridge which in turn results in needle pressure is proportional to the product of the extension of the spring and the sine of the angle ϕ . (Angle ϕ is angle between the axis of the spring and a line drawn through the pivot point to the point where the spring contacts lug 108.)

Change in spring extension is proportional to the change of the cosine of the angle ϕ . By choosing the proper angle ϕ for use with a given spring, the effect of the changing sine can be made to substantially cancel the effect of the changing cosine when irregularities in surface height of the record are encountered.

The needle pressure is thereby kept substantially constant.

In conventional arms, if the arm resonance is to occur at a low frequency, the mass of the arm must be made large. Since the arm is supported by the needle resting on the record, the needle pressure is dependent on the mass which it supports.

Counterbalancing or spring means can be used to obtain a desired needle pressure as long as no variation in the height of the record surface is encountered. However, when surface irregularities are encountered, the entire mass pre-

sented by the arm must be accelerated and the incremental needle pressures may become very large.

In the best commercial transcription devices, arms weighing several pounds are used. This produces effective results as long as a perfectly flat surface is present. Balancing of the arm may produce perhaps less than an ounce of pressure as long as the surface stays flat, but as soon as the arm begins to move up and down, the mass thereof produces, to say, the least, faulty results.

In the present arm, the vertical moment is not dependent upon the transverse moment. The two are independently controlled. Needle pressure is also an independent function. Obviously, the lack of interdependence permits a better integrated design.

Other important features of the cutting head suspension assembly are also, as is now obvious, incorporated in the transcription assembly.

The screw 116 for securing the needle 103 may project through a slot 117 in the front of the arm to assist in supporting the cartridge when the needle is not resting upon the record surface.

Equilibrium may automatically be established in the manner previously described.

The entire transcription head or play back cartridge, its pivots, springs and adjustments may be united as a single sub-assembly to be made by standard mass production methods and mounted as a unit in any standard play-back arm. Other replacement, repair and adjustment features will be clear from the prior discussion.

The turn-table 21 (see Figures 4 and 7) has a pin 90 resiliently mounted therein upon spring 91 which normally forces the pin 90 up through the perforation 92 to project above the top of the turn-table. A record which is to be cut should then have a central perforation by which it may be pushed over the turn-table post 13 and an additional perforation which may register with the pin 90 in the manner shown in Figures 4 and 7 so as to make certain that there is a positive drive for said disk. The pin, since it is not yieldingly mounted with respect to transverse pressures, will thus insure that the disk upon which a record is to be cut will rotate at all times with the turn-table. When a disk upon which a record has been cut is placed upon the turn-table 21 to be played, then it does not matter whether or not it has any perforations for registering with the pin 90 since the resilient mounting of pin 90 upon spring 91 will permit the spring to be depressed by the weight of the record 55 itself. The operation of pin 90, therefore, is completely automatic.

While the entire assembly has been shown as mounted on the surface of the base plate 10, it will be obvious that the mounting plate 12 may be depressed beneath the surface of the base plate 10 and that a circular depression may surround the mounting 12, the said circular depression having as a center the turn-table mounting post 13 so that the top of the turn-table will be virtually level with the base plate 10 and by this means tend to prevent any cuttings from the records or any dust or needles or other small paraphernalia from impeding the operation of the various turn-table rotating mechanisms hereinbefore described.

Where a depression is not desired, virtually the same purpose may, of course, be accomplished by causing the flanges 20 of the turn-table 21 to be sufficiently long to almost be in contact with the top surface of the base plate 10 and thus

reduce the possibility of any material entering the operative elements.

Other elements may be combined with and are useful in the operation of the recording unit herein described. Thus in equipment to be used by a non-technical operator every aspect of confusion must be removed from an indicating means.

In the operation of the cutter, the tendency of the cutting stylus is to force the shavings centripetally. Occasionally, it is possible for shavings to interfere with cutting action.

Various brushing methods have been attempted as means of clearing the shaving away from the cutting radius without much success. We have used a flexible member or finger 200 (Figs. 2, 8 and 1) affixed to the cutting arm by the bolt 201 with its tip located beyond the end of the cutter arm in a position where it contacts the shaving preferably slightly centripetally of the stylus. If the member is of some material (rubber, for example) which has a relatively large coefficient of friction with the shaving, adherence results until the shaving is extended as shown by the dotted lines of Figure 8 to engage the center spindle 13 or the bulk of shaving already accumulated toward the center of the record until it is pulled clear of the member by a winding action. The flexibility of the member aids this clearing operation and causes the tip to return to its normal position after being freed. Because the shaving winds up on a small diameter, the additional power demand on the motor is kept small. Therefore alternate winding of the shaving and clearing of the flexible member from the shaving does not occasion any material change in power demand on the motor which would cause "wows." Obviously, a plurality of fingers may be used if desirable.

It will be noted that by the combination of the foregoing elements, an inexpensive, extremely simple, readily adjustable and easily operable recording mechanism for the lay user has been devised; that the individual elements thereof necessarily cooperate with and influence each other while the various stresses present in each of the elements are not communicated from one element to the other.

As has also been pointed out above, the relationship among each of the members is such that any variation in response which, in the average recording unit might result in the production of high or low frequency disturbances or noises will in the present invention not merely be localized but actually will be compensated.

Thus the resilient mounting of the motor and the resilient connection between the motor and the turn-table results in an ironing out or a smoothing out of the operation of the motor to prevent any disturbing noises from being transmitted from the motor to the turn table.

Likewise, also the lateral feed mechanism of the cutting arm is not directly connected to the motor but is connected to and operated from the turn-table mounting post so that additional elements of isolation thereof from the motor are present. Furthermore, the cutting head of the cutting arm is itself resiliently mounted and so adjusted that variations in the operation of the turn-table resulting in momentary increase or decrease in relative height thereof with respect to the cutting head are compensated for by adjustments of the cutting head itself and by automatic changes in the cutting angle of the cutting stylus which permit compensating variations in

the depth of groove to be cut and which permit therefore an equalization of the pressures upon the cutting stylus so that substantially the original groove depth is maintained.

5 An important element of the mechanism is the fact that the lateral feed of the cutting arm is not directed by any complicated gearing or cam arrangements but is effected by the ordinary operation of a helical screw from the turn-table mounting post causing a pawl attached to an arm of the shaft carrying the cutting arm to move transversely with respect to the turn-table and thus rotate the cutting arm.

In each of the foregoing portions and in the entire constructions there has been described simply the preferred manner of utilizing the various principles herein set forth and the manner in which they have been commercially adapted to use. Obviously the various elements hereof may each take different forms, each within the spirit of the disclosure herein and accordingly I prefer to be bound not by the specific commercial disclosure herein but only by the appended claims.

25 I claim:

1. In a recording apparatus comprising a turn-table having a spindle, said spindle being rotatable with said turn-table, a motor, a power connection from said motor to said turn-table, a cutting arm, a rotatable post carrying said cutting arm, a lateral feed arm carried by said post, said spindle driving a screw, a knife edge pawl on said lateral feed arm engageable with said screw, rotation of said screw moving said knife edge pawl longitudinally thereof and sweeping said cutting arm across the turn-table, said knife edge pawl being resiliently mounted on said lateral feed arm.

2. In a recording apparatus comprising a turn-table having a spindle, said spindle being rotatable with said turn-table, a motor, a power connection from said motor to said turn-table, a cutting arm, a rotatable post carrying said cutting arm, a lateral feed arm carried by said post and a power connection from said spindle to said lateral feed arm for sweeping the cutting arm across the turn-table, said post being slidably longitudinally in a journal, a platform rotatably carried by said journal and fixed with respect thereto against longitudinal movement, a platform carried by said post, the rear end of said cutting arm being pivoted on said post platform, a portion of said rear end projecting beyond said pivot, a link connection between said projecting rear end and said journal platform, and means for exerting constant downward pressure upon said post.

3. In a recording apparatus comprising a turn-table, a cutting arm, and a motor, means interconnecting said motor and said turn-table and cutting arm for driving the same a V-shaped flange secured to said arm; a cutting head resiliently mounted in said cutting arm between the free end of said arm and said flange, said cutting head comprising a cartridge, means at one end thereof for carrying a cutting stylus, a knife edge projection for the opposite and engageable with said V-shaped flange, said cartridge being vertically pivotable about said knife edge, a tension spring secured at one end to a threaded member mounted on said arm and means on said opposite end of said cartridge engaging the other end of said spring, said spring retaining said knife edge against the V of said flange, said threaded member being rotatable for adjusting the axis of said

spring, an opening in the front of the cutting arm, and a screw projecting from the front of the cartridge and engageable with said stylus carrying means for locking the stylus in place in said cartridge, said screw projecting through said front opening of the cutting arm.

4. In a recording apparatus comprising a turn-table, a cutting arm, and a motor, means interconnecting said motor and said turn-table and cutting arm for driving the same a V-shaped flange secured to said arm; a cutting head resiliently mounted in said cutting arm between the free end of said arm and said flange, said cutting head comprising a cartridge, means at one end thereof for carrying a cutting stylus, a knife edge projection from the opposite end engageable with said V-shaped flange, said cartridge being vertically pivotable about said knife edge, a tension spring secured at one end to a threaded member mounted on said arm and means on said opposite end of said cartridge engaging one end of said spring, said spring retaining said knife edge against the V of said flange, said threaded member being rotatable for adjusting the other end of said spring for changing the axis thereof.

5. A sound apparatus comprising an arm and a head carrying a stylus at one end, the opposite end of said head being pivotally mounted in said arm and rotatable vertically in a playless bearing, said bearing comprising means for preventing horizontal movement of said head with respect to said arm, means resiliently engaging said head at said opposite end, and positioning said head with respect to said playless bearing, and means at said stylus carrying end for confining pivotal movement of said cutting head within predetermined limits.

6. In recording apparatus having a horizontal rotatable turn-table and a driving means therefor; a cutting arm mounted on a vertical post pivoted in a journal; said cutting arm being arranged above said turn-table and means for supporting said cutting arm in a position parallel to said turn-table; means for sweeping said cutting arm across the surface of said turn-table; said means comprising a horizontal screw rotatable in synchronism with the turn-table and arranged beneath said turn-table; and a lateral feed arm on said post extending parallel to said turn-table and beneath said turn-table, said arm carrying a knife edge pawl engageable with the threads of said screw, said pawl being rigidly laterally integrated with said feed arm and having no lateral compliance with respect thereto, said pawl being resiliently mounted with respect to the vertical plane and having vertical compliance with respect to said feed arm.

7. In a phonographic recording apparatus comprising a rotatable turntable, and a cutting arm, a screw driven in synchronism with said turntable, a rotatable post carrying said cutting arm, a lateral feed arm carried by said post, a knife edge pawl on said lateral feed arm engageable with said screw, rotation of said screw moving pawl longitudinally thereof and sweeping said cutting arm across the turntable, said pawl being resiliently mounted on said lateral feed arm.

8. In phonographic recording apparatus comprising a rotatable turntable and a cutting arm,

5 a screw driven in synchronism with said turn-table, a rotatable post carrying said cutting arm, a lateral feed arm carried by said post, said post being slidable longitudinally in a journal, a platform rotatably carried by said journal and fixed with respect thereto against longitudinal movement, a platform carried by said post, the rear end of said cutting arm being pivoted on said post platform, a portion of said rear end projecting beyond said pivot, a link connection between said projecting rear end and said journal platform, and means for exerting constant downward pressure upon said post.

9. In phonographic recording apparatus, a cutting arm, a V-shaped flange secured to said arm, a cutting head resiliently mounted in said cutting arm between the free end of said arm and said flange, said cutting head comprising a cartridge, means at one end thereof for carrying a cutting stylus, a knife edge projection from the opposite end engageable with said V-shaped flange, said cartridge being vertically pivotable about said knife edge, a tension spring secured at one end to a threaded member mounted on said arm and means on said opposite end of said cartridge engaging the other end of said spring, said spring retaining said knife edge against the V of said flange, said threaded member being rotatable for adjusting the axis of said spring, an opening in 20 the front of the cutting arm, and a screw projecting from the front of the cartridge and engageable with said stylus carrying means for locking the stylus in place in said cartridge said screw projecting through said front opening of the cutting arm.

10. In phonographic recording apparatus, a cutting arm, a V-shaped flange secured to said arm, a cutting head resiliently mounted in said cutting arm between the free end of said arm and said flange, said cutting head comprising a cartridge, means at one end thereof for carrying a cutting stylus, a knife edge projection from the opposite end engageable with said V-shaped flange, said cartridge being vertically pivotable about said knife edge, a tension spring secured at one end to a threaded member mounted on said arm and means on said opposite end of said cartridge engaging one end of said spring, said spring retaining said knife edge against the V of said flange, said threaded member being rotatable for adjusting the other end of said spring for changing the axis thereof.

11. A recording apparatus comprising a turn-table rotating on a spindle, a cutting arm, and a motor, means interconnecting said motor and said turn-table and cutting arm for driving the same, said cutting arm carrying a cutting head; a cutting stylus for said cutting head; and a flexible member on said cutting arm engaging the recording surface on a smaller radius thereof than is engaged by said stylus and sweeping said surface as said turn-table rotates, said flexible member engaging shavings cut by said cutting stylus and holding portions of said shavings stationary whereby rotation of said turn-table causes the remaining portions of said shavings to be wound up on said spindle.
